UNITED STATES PATENT OFFICE.

WALTER R. GREEN, OF CHICAGO, ILLINOIS.

DESIGN FOR A MUD-GUARD AND BRACKET THEREFOR FOR A MOTOR-CYCLE OR
SIMILAR DEVICE.

47,817.

Specification for Design.

Patented Sept. 14, 1915.

Application filed March 20, 1915. Serial No. 15,960. Term of patent 14 years.

To all whom it may concern:

Be it known that I, WALTER R. GREEN, a citizen of the United States, and residing in the city of Chicago, county of Cook, and State of Illinois, have invented a new, original, and ornamental Design for a Mud-Guard and Bracket Therefor for a Motor-Cycle or Similar Device, of which the following is the specification, reference being had to the accompanying drawings, forming a part thereof.

In the drawings, Figure 1 is a side eleva-

tion of a mud guard and bracket showing my improved design. Fig. 2 is an end view of the same.

I claim:

The ornamental design for a mud guard and bracket therefor, for a motorcycle or similar device, as shown.

WALTER R. GREEN.
